UNITED STATES PATENT OFFICE.

BERNARD A. BEHREND, OF NORWOOD, OHIO, AND EDWIN C. WRIGHT, OF NEWPORT, KENTUCKY, ASSIGNEES, BY MESNE ASSIGNMENTS, TO THE BULLOCK ELECTRIC COMPANY, A CORPORATION OF OHIO.

WINDING FOR DYNAMO-ELECTRIC MACHINES.

SPECIFICATION forming part of Letters Patent No. 783,397, dated February 21, 1905.

Application filed November 6, 1903. Serial No. 180,039.

To all whom it may concern:

Be it known that we, BERNARD A. BEHREND, residing at Norwood, in the county of Hamilton and State of Ohio, and EDWIN C. WRIGHT, residing at Newport, in the county of Campbell and State of Kentucky, citizens of the United States, have invented certain new and useful Improvements in Windings for Dynamo-Electric Machines, of which the following is a full, clear, and exact specification.

Our invention relates to dynamo-electric machines, and particularly to windings for the same; and the object of our invention is to provide a symmetrical continuous winding simple in construction and adapted for the armatures of generators and motors generally, and particularly for the rotor-winding of induction and synchronous motors having a single conductor per slot.

Our invention is especially useful for large machines when conductors of very large cross-section and low resistance are desirable.

With conductors of large cross-section the securing of end connections which shall be simple in arrangement, compact in form, of low resistance, and with good contacts at points of union is of the greatest importance, and in securing this construction we use laminated bar-windings with the end connections lying close to the periphery of the core and a form of joint such that large contact is obtained and the appearance of the conductor kept uniform.

Our invention in its preferred form will be disclosed in the following description and annexed drawings and the novelty thereof set forth in the appended claims.

In the drawings, Figure 1 is a development of a portion of a wave-winding for the rotor of an induction-motor. Fig. 2 is a sectional view through a portion of the rotor on the line 2-2 of Fig. 1. Fig. 3 is an end view of a portion of the rotor, showing only a few windings in position thereon. Fig. 4 is a perspective view of a loop removed from the rotor. Fig. 5 is an enlarged perspective view of portions of one half of a loop, showing the form of joint. Fig. 6 is a similar view of portions of the other half of a loop, and Figs. 7 and 8 are plan

views of the two stampings required to build up the winding. 50

In Figs. 1, 2, and 3 the rotor-core is indicated at 1, having the ventilating-spaces 2 and end plates 3. The latter are provided with shelves 4 for supporting the end connections of the winding. The rotor is provided with 55 the teeth 5, and in the slots formed are located the conductors 6, retained in place by the wedges 7. Only one conductor per slot is used, thereby allowing large cross-section of the conductor, with consequent low resistance. 60

Following a single element in Fig. 1 it will be seen that starting from *a* the conductor passes over several end connections to the slot *b*, then out, and turns within several end connections to *c*, then outside the end connections to slot *d*, then out, and turns within other end connections to *e*, and so on in wave form. The windings may of course be connected up to give the results desired—such as two-phase, three-phase, &c.—but as the specific form of connection for a particular case forms no part of our invention only a portion of the uniform winding is shown. 65 70

The form of the loop is shown in Fig. 4 and will be understood by reference to the same in connection with the other figures. Starting at *a*, at which point a joint is formed, the conductor makes a turn sidewise at *f*. There is then a straight portion *g*, after which the conductor makes a sidewise turn at *h* toward its slot. Then follows a portion which consists of a straight section *i* outside the slot and a straight section *k* within the slot. The conductor then makes an inward turn toward the axis at *l*, bends sidewise at *m*, and in the short straight portion *n* passes within several end connections and bends sidewise at *o*. 85 80

At *c* a joint is formed, and the conductor then passes over other end connections to its slot, having bends and straight sections *f*, *g*, *h*, *i*, *k*, *l*, *m*, and *n* from *c* to *c*, which correspond to those from *a* to *c*. It will be noted that there is only one joint in each loop and that one end of each conductor passes over and the other end passes within other end 90 95 connections.

The structure of the conductor is shown in Figs. 5 and 6 and is built up of thin strips riveted together. This laminated form secures the advantage of reduced eddy or cross currents in the conductor and likewise makes them flexible. The separate strips are stamped out of thin sheet-copper. The stampings A and B are of the form shown in Figs. 7 and 8 and are similar to each other except that A is shorter than B and has a longer extension p at one end. The difference in length of the stampings and the length of the extension p on A over p' on B is equal to the width of the stampings. The bend 7 is stamped out in the strips A B, as shown. Each conductor is built of a number of stampings, four being shown, two of the form A and two of the form B. These are placed together alternately, and thus form spaces r at the ends to receive corresponding extensions of the conductor to which it is to be connected. The conductor shown in Fig. 5 corresponds to that extending from a to c and the conductor shown in Fig. 6 corresponds to that extending from c to e . The conductors are provided with holes s and s' and are riveted together by rivets t and t' . After the strips are stamped out and the holes s and s' punched the conductor is built up and the rivets t , which are inserted in holes s , are headed up and the ends of the strips tinned. Before being placed on the core that end of the conductor in which the bend l and extensions p and p' are formed is bent at m and o to its final shape. The bends f and h are formed by hand after the conductor is in place on the core and the joints are then riveted up by rivets t' in the holes s' and are well soldered. It is evident that the joint thus formed gives large surface contact, and therefore good conductivity and is uniform in appearance with the rest of the conductor. The end connections are held in place on the shelves 4 by band-wires 8, a sheet of insulating material 9 being located between the band-wires and the end connections. The conductors are insulated from the core and from each other by use of the customary materials.

With reference to the winding generally it is seen that a single bar per slot is used and that the end connections lie close to the periphery of the core, as shown in Fig. 3, one portion thereof, from a to i , lying the same distance from the axis as the bars themselves and the other portion, from c to l , lying nearer the axis by a distance approximately equal to the depth of the conductor.

While we have described our winding as applied to the rotor of an induction-motor, we do not limit ourselves to this specific application, as our invention may be equally well applied to armature-windings generally whether applied to the rotating or stationary part of the machine. Likewise our novel form of joint could be used in any winding in which laminated conductors are used and can be used

equally well in a straight or curved portion of the conductor.

We claim as our invention—

1. A winding for dynamo-electric machines having toothed cores, comprising a single conductor per slot, and end connections, half of said end connections being the same distance from the axis of the machine as the main portion of the conductors, and the other half of said end connections being nearer the axis by a distance approximately equal to the depth of the conductors, the end connection of each conductor at one side of the core passing over and at the other side of the core passing under other end connections, substantially as described. 70 75 80

2. A winding for dynamo-electric machines having toothed cores, comprising a single conductor per slot, each conductor having end connections integral therewith, one of said end connections lying the same distance from the axis of the machine as the main portion of the conductor, and the other lying nearer the axis by a distance approximately equal to the depth of the conductor, the end connection of each conductor at one side of the core passing over and at the other side of the core passing under other end connections, substantially as described. 85 90

3. A winding for dynamo-electric machines, comprising conductors having end connections integral therewith, the end connection of each conductor on one side of the core being the same distance from the axis as the main portion of the conductor, and the end connection of the same conductor on the other side of the core lying nearer the axis by a distance approximately equal to the depth of the conductor. 95 100

4. A winding for dynamo-electric machines having toothed cores, comprising a single conductor per slot, and having end connections integral therewith, the end connections for each conductor having a double bend sidewise on each side of the core and on one side of the core having a bend toward the axis of the machine. 105 110 115

5. A winding for dynamo-electric machines, comprising conductors having end connections integral therewith, each conductor having two sidewise bends at each side of the core, an inward bend toward the axis of the machine between the core and the two sidewise bends at one side of the core and an outward extension at one end of the conductor. 120 125

6. A winding for dynamo-electric machines, comprising conductors and end connections formed integral therewith, each conductor having two sidewise bends as f and h on one side of the core, two sidewise bends as m and o on the other side of the core, an inward bend as l between the core and the bend m and an outward extension at one end of the conductor. 130

7. A winding for dynamo-electric machines having laminated conductors, alternate laminæ

of each conductor being shortened at the end to form a joint with the corresponding end of another conductor.

8. In a winding for dynamo-electric machines having laminated conductors, a joint therefor formed by alternate laminæ of each conductor being shortened at the ends, the longer laminæ of each conductor occupying the space formed by the shortening of alternate laminæ in the other conductor and means to bind the laminæ together.

9. In a winding for dynamo-electric machines having laminated conductors, a joint therefor formed by alternate laminæ of each conductor being shortened at the ends, the longer laminæ of each conductor occupying the space formed by the shortening of alternate laminæ in the other conductor and rivets passing through the laminæ to bind them together.

10. In a winding for dynamo-electric machines having laminated conductors, a joint therefor formed by alternate laminæ of each conductor being shortened at the ends, the longer laminæ of each conductor occupying

the space formed by the shortening of alternate laminæ in the other conductor and rivets passing through the longer laminæ of each conductor to bind them together and other rivets near the joint for binding the laminæ together.

11. In a winding for dynamo-electric machines having a single conductor per slot, comprising laminated conductors and end connections integral therewith, the end connection of each conductor having two sidewise bends as *f* and *h* on one side of the core, two sidewise bends as *m* and *o* and an inward bend as *l* between the core and the bend *m* on the other side of the core and an outward extension at one end of the conductor, alternate laminæ being shortened at the ends of the conductor to form the joints with other conductors.

In testimony whereof we affix our signatures in presence of two witnesses.

BERNARD A. BEHREND.
